Primary Examiner — Lilyana Bekic*Assistant Examiner* — Elizabeth Sun Ko(74) *Attorney, Agent, or Firm* — Bodman PLC(57) **CLAIM**

The ornamental design for a ground anchor bracket, as shown and described.

DESCRIPTION

FIG. 1 is a front, top, and left perspective view of the ground anchor bracket with a connection shoe attached;

FIG. 2 is a front, top, and left perspective view thereof without the connection shoe attached;

FIG. 3 is a top plan view thereof;

FIG. 4 is a bottom plan view thereof;

FIG. 5 is a front view thereof, the rear view being a mirror image; and,

FIG. 6 is a side view thereof.

The broken lines in FIG. 1 showing the connection shoe depict environmental subject matter that forms no part of the claimed design.

All other broken lines in the drawings depict portions of the ground anchor bracket that form no part of the claimed design.
